UNITED STATES PATENT OFFICE.

GUSTAV P. HELFRICH, OF NEW YORK, N. Y.

TORPEDO.

1,117,843.

Specification of Letters Patent. Patented Nov. 17, 1914.

Application filed November 15, 1913. Serial No. 801,149.

To all whom it may concern:

Be it known that I, GUSTAV P. HELFRICH, a citizen of the United States, and a resident of the city of New York, county of the Bronx, and State of New York, have invented a new and Improved Torpedo, of which the following is a full, clear, and exact description.

This invention relates to improvements in 10 torpedoes, and has for an object to provide an improved structure for steering a torpedo, and for providing means for indicating the path traveled by the torpedo so as to allow for correct steering.

15 Another object of the invention is to provide an improved structure which will send a spray of water to an appreciable height above the surface of the water in which the torpedo is arranged, and also to project a 20 light upwardly from the torpedo.

A still further object of the invention is to provide a graduated solenoid structure for controlling the supply of current to the various parts of the torpedo so that by 25 proper energization of the solenoid any of the parts desired may be properly actuated for causing the torpedo to act in the desired manner, as for instance moving to the right or left.

30 In carrying out the object of the invention a torpedo shell of substantially any kind is provided, and is provided with a propeller at the rear, and with a plurality of partitions intermediate the length of the 35 shell so as to divide the shell into independent compartments. The center compartment is preferably open at the top and bottom, and has arranged therein a spool carrying insulated wire, which wire has one 40 end connected with a suitable current supply on the shore, and the other end of the wire connected to conductors designed to distribute current to the various current receiving devices in the inclosed compartments. The front compartment is designed 45 to receive an explosive, and when current is supplied thereto the spark caused thereby will result in the ignition of the explosive. The rear compartment is supplied with various 50 motors and other means for causing the torpedo to be propelled and to be guided in its travel. The rear compartment also contains means by which a jet of water is forced to any desired distance above the torpedo. The front point of the torpedo may 55 be provided with the usual war head.

In the accompanying drawings—Figure 1 is a view of a torpedo embodying the invention, the principal parts thereof being shown in longitudinal section, the torpedo 60 being shown as submerged in a body of water; Fig. 2 is a sectional view through the rear of a torpedo, the same being shown on an enlarged scale for better disclosing the various operating parts; Fig. 3 is a side 65 view of the wire carrying spool or drum, certain parts being broken away for better illustrating the construction; Fig. 4 is a diagram showing the wiring in the torpedo and the controlling means on shore; Fig. 5 70 is a detailed fragmentary side view of a switch arranged in the torpedo; Fig. 6 is a view similar to Fig. 5 except showing certain of the parts moved to a new position.

Referring to the accompanying drawings 75 by numeral 1 indicates the shell of the torpedo which may be of any desired size, and substantially of any shape, the same preferably, however, following the usual shape of torpedoes now in use. At the rear a propeller 2 is provided which is mounted upon a suitable shaft 3 driven by motor 4 through shaft 5 and gear wheels 6 and 7. The motor 4 receives current from a suitable source of supply 8 arranged on the shore (Fig. 4) 80 through the wire 9 wound upon spool or drum 10. It will be observed that the shell 1 is provided with partitions 11 and 12 so as to present a forward compartment, a rear compartment and an intermediate compartment. The intermediate compartment is 85 where spool 10 is located, and is preferably open to the sea. The forward compartment is provided with any desired kind of an explosive 13, which explosive is adapted to be 90 ignited or exploded by a fuse 14 when the same receives the proper current for blowing. In order that the torpedo may be better balanced the explosive 13 is arranged in the lower portion of the shell 1, whereby an 95 upper compartment 15 is presented. It will also be evident that guiding fins or other suitable guiding means could be used for preventing the rotation of the shell 1. Though guiding fins or other means may be 100 provided for properly holding the torpedo in a correct position it is preferred to use a propeller which rotates in one direction for driving the torpedo and to utilize the rotation of the spool or drum 10 which is 105 adapted to rotate in the opposite direction to the propeller and thereby counteract the

rotating effect of the propeller. In this way a smooth casing with few or no guiding fins may be readily used and the torpedo properly maintained upright.

When motor 4 rotates shaft 5 not only is the propeller 2 driven but also a pump 16 is driven for supplying water to the distributing pipe 17. From pipe 17 water is distributed to the jet pipe 18 after the same has passed through valve 19. Valve 19 is provided with a controlling arm 20 which acts as an armature to magnet 21, whereby whenever magnet 21 is energized valve 19 will be opened and water from pump 16 will be discharged out of the jet pipe 18, as shown in Fig. 1. Valve 19 is provided with a spring (not shown) which tends to maintain the valve closed so that when the magnet 21 is deenergized the valve is automatically closed. The particular construction of the valve forms no part of the invention and will therefore not be described in detail as any common form of spring valve which automatically closes can be used provided the same is supplied with an operating member 20 which is of magnetic material so as to act as an armature for magnet 21.

Supply pipe 17 (Fig. 2) supplies water to the various valves 22, 23, 24 and 25, which valves control the various discharges 26, 27, 28 and 29. The discharge members or pipes 27 and 28 are designed to steer the torpedo, and to cause the same to turn either to the right or left, while the tubes 26 and 27 are designed to control the depth of the torpedo. The discharge of the water out of any of these tubes will cause a corresponding movement in the rear of the torpedo which naturally will cause the point or forward end to be pointed in a different direction and consequently properly steered or caused to properly attain the correct depth. The valves 22 to 25, inclusive, are of the spring variety similar to valve 19, and are provided with operating levers 30, 31, 32 and 33 formed of magnetizable material so as to be attracted by the magnets 34, 35, 36 and 37, respectively. When any of these magnets are energized the valve associated therewith will be opened, and when deenergized the valve will automatically close. The circuits of these magnets are clearly shown in Fig. 4 and will be pointed out in detail hereinafter. Arranged in the rear compartment and connected in any desired manner with the spool or drum 10 is a motor 38 which is supplied with current from the supply 8 on the shore as long as the current is supplied to motor 4 so that spool 10 will be given a tendency to rotate and thereby assist the wire 9 in rotating the spool. The motor 38 may be of any desired power, but is preferably only sufficiently strong to rotate the spool, while empty, and thereby require a pull upon wire 9 to cause the same to unwind. In this way

the wire is relieved of the principal part of the strain and will readily unwind without injury. As shown in Fig. 3 the wire 9 is passed through an aperture 39 in the sleeve 40 and is secured rigidly to a metallic shell 41 on which is arranged a brush 42. Shell 41 is insulated from sleeve 40 by a suitable strip of insulation 43 and the sleeve 40 is also insulated from shaft 44 by an insulating shaft 45. Member 41 is rigidly secured to the spool or drum 10 and extends through partition 11, while shaft 44 is rigidly connected with sleeve 40 so as to rotate therewith, and with spool 10. Any kind of packing may be provided for preventing water from passing from partition 11 into the rear compartment or into the front compartment through partition 12. The current from wire 9 passes on to the sleeve 41 and from thence to brush 42 and from brush 42 to the various parts in the rear compartment for causing the proper operation of such parts. The current from brush 42 also passes through certain elements and finally to brush 46 and from brush 46 through shaft 44 to a slip connection 47 of any desired kind and from thence to fuse 14 to the ground. By these means whenever brush 46 is switched into the circuit of wire 9 fuse 14 will be blown. When fuse 14 is blown the pivotally mounted member 105 will move downwardly and engage the socket 106, member 105 acting as the knife of an ordinary knife switch, and member 106 acting as a socket. When fuse 14 is blown member 105 moves by weight downwardly and engages the socket 106 so that current passes from knife 105 to wire 107 through socket 106, and from thence through fuse 108 to the ground. The fuse 108 is arranged to ignite or cause the explosive matter to explode. The fuse 14, however, is separated somewhat from the explosive matter and may be provided with a housing so as to prevent the explosive matter from coming in contact therewith. However, the housing must allow member 105 to properly swing so as to engage socket 106 when fuse 14 has blown. This is very desirable as current passing through the wire from spool 10 might set up a small current in member 44 and thereby heat to a greater or less extent the fuse 14, which would be objectionable in case fuse 14 was in contact with the explosive. By providing means as shown in Fig. 4 it will be necessary to blow fuse 14 before the explosive can be exploded.

Referring particularly to Fig. 4 a complete diagram will be seen showing how the current flows through the various devices, and how the various devices are controlled. On the shore is arranged a source of power 8 and a rheostat 48. The rheostat 48 is provided with an arm 49 and with resistance coils 50, 51, 52, 53 and 54 which are

connected up with the respective contacts 55, 56, 57, 58, 59 and 60. Contact 60 has connected therewith wire 9, whereby current may be passed from the source 8 to sleeve 40 and from thence through brush 42, wire 43, solenoid 61, wire 62, wire 65 and spring arm 66 to any of the contacts 67, 68, 69, 70 and 71 according to the position of arm 66. The arm 66 is made of spring material, and preferably a good conductor so as to press against the various contacts 67 to 71, inclusive, for allowing the current to properly pass to the various devices in the rear compartment and also to the fuse 14 under some circumstances, is provided. When arm 66 is in the position shown in Fig. 4 the current will not pass through the same as the arm is resting upon a piece of insulation. However, current will pass through solenoid 61, wire 62, the swinging arm 72, wire 73, and from thence to the feed wire 74 which is designed to supply current to motors 4 and 38. Current passing from these motors will traverse wire 75 and a common return wire 76 to the ground. The current passing this way will be sufficient to operate motors 4 and 38, but will not be sufficiently strong to magnetize the solenoid 61 to a proper extent for attracting the core 77, and therefore arm 66 will not be moved. When the switch arm 49 on the shore is moved so as to contact with contact 55 current will flow in the last circuit described, namely, through the motors, and will not affect any of the other devices. This is true with the exception of the diving magnet 34. Current will divide at arm 72 and part will pass to the motors and part will pass through wire 78 to the contact 79 and from thence to a second contact 80. From contact 80 current will pass through wire 81, magnet 34, wire 82 to the common return 76 to the ground. Current will flow in this circuit until the torpedo has dived a sufficient distance to allow the pressure of the water acting on plunger 83 to move contact 79 out of engagement with contact 80 against the action of spring 84. As long as these contacts are separated magnet 34 will be deenergized. If for any reason the torpedo should shift deeper than desirable the water pressure would cause the contact 79 to engage member 85 so that current will flow from wire 78 through contact 79, member 85, wire 86, magnet 37, wire 87 to the common return 76, and from thence to the ground. This will cause valve 25 to be opened and water to pass through tube 29 so as to depress the rear end of the torpedo 60 and thus point the torpedo in an upward direction. This circuit is maintained until the pressure on plunger 83 has been sufficiently relieved for breaking the engagement of contact 79 and member 85. By providing members 80 and 85 the depth at which the

torpedo travels is automatically controlled. It is of course understood that spring 84 could be of any desired strength so as to maintain the torpedo at the desired depth which is preferably only a short distance 70 below the surface of the water.

When the arm 49 of the controlling device on the shore is moved to contact 56, resistance 50 will be cut out so that a more powerful current may pass to solenoid 61 and thereby attract the core 77 a sufficient distance for causing arm 66 to engage contact 67. When this is done part of the current will pass through wire 65 to arm 66, contact 67, wire 86, magnet 21, wire 88 and common 80 return 76 to the ground. When magnet 21 has been energized the water jet valve 19 will be opened and water from pump 16 will be forced through pipe 18 for forming the jet shown in Fig. 1. In case it is desired to turn the torpedo so as to move it to the left, arm 49 on the shore is moved to a position in engagement with contact 57, whereupon resistance 51 will be cut out and therefore an additional supply of current 85 will pass through solenoid 61. This will cause arm 66 to move over to a position in contact with the contact segment 68, whereupon current will flow from arm 66, through segment 68, wire 89, magnet 35 and wire 90 to the 95 common return 76, and from thence to the ground. This will cause valve 23 to open and water to pass through pipe 27 so as to properly shift the torpedo. If it should be desired to turn the torpedo to the right, arm 100 49 on the shore would be moved over so as to contact with member 58 and thus cut out resistance 52. This lessening of the resistance of the line will cause a larger current to flow through solenoid 61, whereby arm 105 66 will be turned over so as to engage the contact member 69. When arm 66 is in engagement with contact 69 current will pass from arm 66 through wire 69, wire 91, magnet 36, and wire 92 to the common return 110 76, and from thence to the ground. The magnetization of magnet 36 will cause valve 24 to be opened and water to flow through pipe 28 so as to turn the torpedo to the right. If it should be desired to light the lamp 93 the arm 79 on the shore will be moved so as to engage contact 59 and thereby cut out resistance 53. By cutting out resistance 53 an additional amount of current will flow through solenoid 61 so as to cause 115 arm 66 to move to a position in engagement with contact 70. It is to be understood that the movement of arm 66 is caused by a pull against the action of spring 94. While arm 66 is in engagement with contact 70 current will flow from arm 66 through contact 70, wire 95, lamp 93 and common return 76 to the ground. Lamp 93 will burn as long as arm 66 is in engagement with contact 70. Whenever it is desired to explode the ex- 120 125 130

plosive matter 13 in the torpedo, arm 49 on the shore is moved to a position in engagement with contact 60, whereby resistance 54 will be cut out, and in fact all of 5 the resistance will be cut out so that the full current will flow over wire 9 into the torpedo. The passage of the full current through solenoid 61 will cause arm 66 to move over and engage contact 71. As arm 10 66 engages contact 71 projection 96 which is provided with an insulated end 97 strikes against the contact lever 72 and disengages the same from wires 73 and 78. Member 66 is provided with a hook adapted to catch 15 and interlock with a suitable projection so as to lock arm 66 in contact with the contact 71 and thereby permit the current to freely flow from wire 9, through shell 41, brush 42, wire 43, solenoid 61, wire 62, wire 65, 20 arm 66, contact 71, wire 98, brush 46, shaft 44, wire 47, fuse 14, and from thenec through wire 99 to the ground. Current flowing in this circuit will cause fuse 14 to ignite the explosive matter 13. By moving the arm 25 66 over to contact 71 all of the current receiving devices will be cut out including motors 4 and 38, by end 97 striking contact lever 72 and moving the same out of engagement with wires 73 and 78, whereby 30 the entire current is switched on to the fuse 14. It is of course evident that none of the devices in the torpedo need be further operated when the time comes for exploding the torpedo so that there is no objection to cutting 35 out all of these devices and utilizing the entire current for igniting the explosive. Sometimes it is desirable to move arm 66 quickly from contact 67 to contact 70, or to some intermediate contact, and without supplying current to the intermediate devices. 40 In order to allow the arm to be moved to any particular contact without switching current on to the previous contact the devices shown in Figs. 5 and 6 are utilized for holding arm 66 slightly raised above the various 45 contacts. A plurality of substantially pointed members 100 are arranged in connection with the supporting body 101, all of which are connected together by a link 102, link 102 being connected with members 100 by pivotal pins in any desired manner, and the pivotal mounting of members 100 may be done in any desired manner so that when 50 in their normal position, as shown in Fig. 5, they will occupy a place between the various contacts. If it should be desired to move the arm 66 to contact 68 without contact with contact 67 the arm is quickly brought over to contact 68 and the various 55 members 100 will act as shown in Fig. 6. It will be observed that a quick movement over the first member 100 will cause arm 66 to jump contact 67 and thereby prevent any current passing into contact 67. If there 60 should be a slight contact it would be so 65

momentary as not to appreciably affect the devices connected with contact 67. Suitable stops 103 and 104 are provided for limiting the swinging movement of members 100. It is of course understood that arm 66 is 70 moved normally or step by step across the various contacts through the action of solenoid 61 and not manually. It will be noted that the light 93 is arranged adjacent the discharge nozzle or member 18, whereby the 75 light may illuminate the water jet from nozzle 18. This allows the observer on the shore to properly guide or steer the torpedo at night or at dusk.

What I claim is—

1. In a device of the character described, means for indicating the location of torpedoes comprising a conduit extending in an upward direction, means for ejecting fluid from said conduit to provide a visible elevation in the water above the torpedo to serve as a visible marker, a pump for forcing said fluid through said conduit, a valve for controlling the flow of fluid through said conduit, an arm for controlling said 90 valve, said arm being formed with an armature, a magnet adapted to attract said armature for moving said valve, a wire connected with said armature, a spool on said torpedo for carrying a supply wire, and means on 95 the shore connected with said wires for supplying current thereto.

2. In a device of the character described, means for indicating the location of torpedoes comprising an upwardly directed tubular member, means for ejecting fluid therefrom to provide a visible elevation in the water at the surface over the torpedo to serve as a visible marker, and means for projecting a beam of light upwardly so as 105 to occupy a position adjacent said elevation of water.

3. In a device of the character described, means indicating the location of torpedoes comprising an upwardly directed conduit, 110 means for ejecting fluid therefrom for providing a jet of water extending an appreciable distance above the water so as to serve as a visible marker, a pump for forcing said fluid through said conduit and steering tubes 115 connected with the torpedo, means for switching water from said pump to said steering tubes so as to control the direction of movement of the torpedo, a motor for driving said pumps, and a wire connected 120 with said motor and with a source of current on the shore for operating said motor.

4. In a device of the character described, means indicating the location of torpedoes comprising an upwardly extending conduit, 125 a pump for forcing water through said conduit so as to provide a jet of water an appreciable distance above the surface of the water in which the torpedo is positioned, means for supplying a light adjacent said jet of water, 130

and means on the shore controlling said light and said jet of water.

5. In a torpedo, a propelling member, a plurality of steering tubes, a pump for forcing water through said steering tubes for steering the torpedo, a wire carrying drum, a wire wound on said drum with one end on shore, a motor connected with said wire for driving said pump, a light connected with 10 said wire, an upwardly extending tube, means for connecting the upwardly extending tube with said pump, whereby there will be thrown a jet of water an appreciable distance above the water, means connected with 15 said wire for controlling the flow of water through said conduit, a source of current on the shore for supplying current to said wire, and means interposed between said source of current and said wire for varying the flow 20 of current through said wire, whereby the various devices connected with said wire may be properly controlled.

6. In an exteriorly controlled torpedo, a torpedo structure, means for driving said 25 torpedo structure, said means including an electric motor, a pump connected with said motor, a plurality of steering tubes connected with said pump, a valve interposed in each of said tubes, an electrically operated member for controlling said valves, a wire 30 carrying member arranged in said torpedo, a wire wound on said wire carrying member with one end in electrical communication with said motor, and with electric means for 35 controlling said valves, a source of current on the shore and connected with one end of said wire, and a current controlling member arranged on the shore interposed in said wire.

7. In an exteriorly controlled torpedo, a 40 torpedo structure, a propelling mechanism including a motor, a pump connected with said motor, a plurality of steering tubes connected with said pump, a valve in each of 45 said steering tubes, electric means for controlling said valves, a controlling member connected with said electric controlling means, a wire connected with said controlling member, and with said motor, said 50 wire extending to the shore, a spool for carrying part of said wire on said torpedo, a source of current on the shore, and a rheostat 55 controlling mechanism connected with said source of current, and to said wire, whereby current having different strength 60 may be supplied to the torpedo for driving and steering the same.

8. In an exteriorly controlled submarine 65 torpedo, a torpedo structure including the usual shell, an explosive receiving chamber, a propelling mechanism for the torpedo including an electric motor, an electric contact wire extending from said torpedo structure to

the shore, said electric wire being connected with said motor, a pump connected with said motor, a plurality of steering tubes connected with said pump, a valve interposed in each of said steering tubes, an electric member for controlling said valves, a switching device for controlling the supply of current to the respective electric members, said electric switching device being connected with said wire in multiple with 70 said motor, a source of current arranged on the shore, and a rheostat arranged on the shore corresponding to said switch mechanism and adapted to act substantially synchronously therewith, whereby any of the valves in said steering tubes may be actuated. 75

9. In an exteriorly controlled submarine 80 torpedo, a torpedo structure provided with the usual casing and explosive receiving compartment, a propelling mechanism including an electric motor, a pump connected with said motor, steering tubes connected with said pump, a valve arranged in each 85 of said steering tubes provided with springs for normally holding the same closed, an electric magnet for each of said valves for opening the same against the action of said springs, whereby when any of said valves 90 are opened water will be forced through the respective tubes for turning the torpedo, and when said magnets are deenergized the respective valves will be automatically 95 closed; a propeller connected with said magnets, said propeller being arranged in said shell and provided with a plurality of segments insulated from each other, a swinging arm designed to be brought into contact with any of said segments, a core member 100 connected with said arm, a solenoid for attracting said core, whereby the arm is moved over said segments according to the energization of the solenoid, a supply wire extending from the shore to the torpedo and 105 connected in multiple to said motor and to said controller, and a rheostat arranged on the shore corresponding to said controller, whereby when said rheostat on the shore is moved from one contact to the other the arm of said controller will be likewise moved so as to cause any of said magnets to be energized in order to properly steer the torpedo, and a fuse arranged to be brought into the 110 circuit of said supply wire when the arm on said controller is moved to its extreme position under the action of said solenoid. 115

In testimony whereof I have signed my name to this specification in the presence of two subscribing witnesses.

GUSTAV P. HELFRICH.
